UNITED STATES PATENT OFFICE

WILLIAM OTTO, OF LEISNIG, GERMANY

CARD CLOTH HAVING A FELT LAYER

Application filed September 12, 1927, Serial No. 219,062, and in Germany April 19, 1927.

The present invention relates to card cloths having a felt layer.

The known card cloths provided with a felt layer have the disadvantage that the cards 5 obtained by means of this cloth are easily damaged in use and therefore do not usually last long.

A considerable amount of fibrous material adheres to the rough felt surface and, on 10 cleaning the card, partial brushing out of the felt layer of the card cloth along with the adherent threads cannot be avoided so that the felt layer soon becomes thin and non-uniform. The resistance of the card wires consequently drops since on decrease in thickness 15 of the card cloth only a shorter end of the legs of the card wires is led into the cloth. Finally after a short time the operation of the card wires also leaves something to be desired since 20 each leg of the card wires on moving to and fro impresses a slit like depression in the felt layer in which it oscillates to and fro without the resilient felt mass acting on the wire.

It has accordingly already been proposed to 25 glue a thin sheet of pure rubber, cut in the cold, on to the felt layer as a protective coating. A rubber layer of this type is however very sensitive and easily pulls away on stripping with the hand card so that shreds of the 30 rubber layer are pulled out along with portions of the felt. Also the protective layer of rubber dissolves on the action of oil and is not reliable in the sun and heat. Finally the flat smooth coating of rubber adheres badly to the 35 felt layer.

These disadvantages existing in card cloths having a felt layer are avoided according to the invention by mounting a covering layer of vulcanized rubber on the felt layer and securing this thereto by means of a layer of thread as resilient as possible, for example, a loose or porous cotton cloth.

The vulcanization of a rubber layer on the felt layer of the card cloth is impossible in 45 view of the animal substances contained in the felt. The layer of thread provided according to the invention, for example a loose or porous cotton cloth, under the covering layer allows of a layer of vulcanized rubber 50 being applied to the card cloth with the felt

layer instead of the known cover of pure rubber.

The method adopted according to the invention is to mount the rubber first on a fabric 55 layer preferably cotton, and to vulcanize it thereon, the covering layer so obtained being then secured to the felt layer by means of a solution of rubber, cement or other adhesive.

The fabric layer, which on vulcanization, 60 acts as a support for the rubber mass and is united with the latter, should be as resilient as possible so as to reduce the elasticity of the rubber layer as little as possible by the layer of thread. This fabric layer allows of a secure union between the rubber and the felt 65 layer on gluing the fabric layer supporting the vulcanized rubber on to the felt layer, so that a surprising adherence of the whole covering layer is obtained which is essentially greater than that of a simple layer of non- 70 vulcanized rubber.

The improved card cloth having a felt layer and covering layer of vulcanized rubber 75 possesses to a greater degree the advantages of the card cloth with a felt layer. Cards prepared therefrom are accordingly more suitable than cards of the known card cloths with unprotected thicker layers of milled woolen felt, particularly for spinning wool and similar purposes. The thin card cloths provided 80 with vulcanized rubber layers hitherto known which consisted solely of woven fabric could on the other hand, only be used for preparing cards for cotton spinning.

The felt layer in the improved card cloth 85 can exert its favourable action on the movement of the card wires permanently without damaging this layer in any way on cleaning. The vulcanized rubber layer is itself extraordi- 90 narily resistant to damage, adheres firmly to the felt layer and is not dissolved or injured by oil and heat. Further, less fibrous material adheres to the smooth rubber surface of the card cloth than to a rough unprotected felt surface.

A section of a card cloth on the fabric base 1 of which is arranged a felt layer 2, in the usual manner is shown in Fig. 1 of the drawings as a form of construction of the invention. A vulcanized rubber layer 3 which is 100

vulcanized on a fabric layer 4 is glued to this felt layer as a covering layer. The fabric layer 4 produces a secure union between the covering layer 3 and the felt layer 2.

5 Figure 2 is a cross section through the improved card cloth showing the improved arrangement of the separate layers in card cloths provided with a felt layer.

I declare that what I claim is:—

- 10 1. A card cloth consisting of a fabric base and a felt layer cemented to the said fabric base and provided with a covering layer of loose cotton cloth cemented to the felt and having a previously vulcanized layer of rubber.
- 15 2. A method of producing a card cloth consisting of mounting a layer of felt on a fabric base, coating a loose cotton cloth with a layer of vulcanizable rubber, vulcanizing said layer of rubber and then fastening the said cotton cloth to the layer of felt by means of an adhesive substance.
- 20
- 25

In testimony whereof, I have signed my name to this specification at Leipzig, Germany, this 18th day of August, 1927.

WILLIAM OTTO.
